ATTORNEYS:

UNITED STATES PATENT OFFICE.

JAMES W. McFARLAND, OF LOS ANGELES, CALIFORNIA.

RADIATOR.

1,233,081.

Specification of Letters Patent. Patented July 10, 1917.

Application filed August 14, 1916. Serial No. 114,759.

To all whom it may concern:

Be it known that I, JAMES W. McFARLAND, a citizen of the United States, residing at Los Angeles, in the county of Los Angeles and State of California, have invented new and useful Improvements in Radiators, of which the following is a specification.

This invention relates to a radiator and particularly pertains to an improved construction of the water cells, and means for securing the cells in relation to each other.

It is an object of this invention to construct a radiator of the cellular type which is provided with water circulating cells of a simple and improved construction which insures that they may be readily assembled to form the completed radiator and that they may be made from an element formed with a single set of dies.

Another object of this invention is to provide a radiator having water cells which allow a free circulation of water therethrough and subject it to the cooling action of the atmosphere and which is so constructed that there are no sharp corners or narrow crevices within the cells which might gather sediment or become corroded, or subject to breakage.

Another object is to provide the cellular sections of the radiator with a construction which will allow them to be readily sealed in a water tight manner.

Another object is to provide the water cell section with connecting members which secure them together and will insure that the radiating surface of each cell will be exposed to the cooling effect of the atmosphere and that an unobstructed path of travel will be established through the radiator and between the cells.

Another object is to provide the connecting members with flexibility so that the adjacent water cell sections may be adjustably spaced in relation to each other and in this manner allow the proportion of air circulation and the water circulation to be individually determined according to the requirement of the engine for which the radiator is provided.

It is a further object to provide the radiator of the above construction which is simple in its method of manufacture, extremely light in weight and may be assembled and repaired without difficulty.

A further object is to provide a radiator

construction which permits single sections of water cells to be removed and replaced without mutilation of any of the remaining cells.

Other objects will appear hereinafter.

The invention is illustrated, by way of example, in the accompanying drawings in which:

Fig. 1 is a view in front elevation of a radiator constructed according to the present invention.

Fig. 2 is an enlarged view in detail illustrating a pair of adjacent water cell units and the flexible connecting element therebetween, and also shows a part broken away to disclose the cell formation.

Fig. 3 is a view in end elevation of a portion of the connecting element.

Fig. 4 is a view in side elevation of the elements shown in Fig. 3.

Fig. 5 is a view in elevation of a portion of one of the water circulating units and further illustrates disposition of the connecting elements thereupon.

Fig. 6 is a view similar to a view shown in Fig. 2 and illustrates the manner in which the water circulating elements may be compressed in relation to each other.

Fig. 7 is a view in plan illustrating in a fragmentary manner the arrangement of the water circulating units and the connecting elements to form a radiator of the V type.

Referring more particularly to the drawings, 10 indicates a radiator housing which is adapted to inclose and support a series of water circulating units 11 which are vertically disposed and are adapted to lie parallel to each other. These units are formed from a single strip of metal which is folded upon itself to form a circulating passage-way 12 which may also be termed a water cell. The blank from which the units are formed is made with a series of outwardly extending corrugations 14 which lie parallel to each other and are spaced a uniform distance apart, an arcuate wall 15 intervenes between the corrugation 14 and the corners formed by the corrugations and the walls are all rounded so that there will be

no opportunity for water pockets or corrosion within the cells. When the units 11 are constructed the blank is folded so that the corrugations extend outwardly and in staggered relation to each other and upon opposite sides of the element thus causing the arcuate wall 15 to occur opposite the

110

corrugation 14. This arrangement forms a sinuous path of travel for the water as it circulates through the unit. The opposite ends of the walls 15 are straight and when 5 brought together will lie against each other and may thus be easily soldered to form a water tight passageway between the opposite walls of the unit.

The assembled water circulating units 10 are positioned in parallel relation to each other and are so arranged that the corrugations upon the sides of the units will be interposed in staggered relation to each other so that connecting strips 16 may be soldered 15 to these corrugations and permit the units to be yieldably united. These strips are formed of some flexible material and are sinuous in their formation, thus allowing the corrugation walls to be alternately secured thereto and mounted within depressions 17 and 18 formed upon the oppositely disposed bends of the strips. As shown in 20 Fig. 2 this will space the units apart from each other in a flexible and uniform manner.

It is sometimes found that the radiation provided for an engine is not sufficient to accommodate the demands placed upon it and in such a case it is desirable to increase 30 the circulating capacity of the radiator without enlarging the housing within which the units are mounted. This requirement is met by the flexibility of the connecting strip 16 which may be bent as 35 shown in Fig. 6 of the drawings to permit the water circulating units to be placed in closer relation to each other than they are normally, as shown in Fig. 2; in this manner considerable added space is provided and 40 more units may be added as required.

In forming a radiator of the V type it is necessary to construct the connecting strips 19 in an offset manner thus permitting the water circulating units to be placed parallel 45 to each other and each slightly in advance to each other to conform to the V shape housing.

In the formation of this radiator the strips 11 are first run through a die and 50 formed with the corrugations 14 and the arcuate intervening walls 15. After the blanks have thus been acted upon they are

folded upon each other to form the units 11 as clearly shown in Fig. 2 of the drawings. This provides a circulating passage 55 12 for the water as will be readily understood. The separate units are then soldered along their edges in a water tight manner, and are thereafter soldered to the strips 16. This forms a completed radiator which may 60 be placed within its housing 10 and there arranged to be provided with water and circulation thereof. In case the assembled radiator is too wide for the housing the units may be forced toward each other as 65 the strips 16 collapse.

It will thus be seen that the radiator here provided is simple in construction, is formed of few component parts and is easily adapted to various width radiator housings.

I claim:

1. A radiator core for internal combustion engines, comprising, a series of parallel water circulating units, and means 75 whereby said units may be flexibly disposed in adjustable relation to each other.

2. A radiator core for internal combustion engines, comprising, parallel water circulating units, and flexible strips interposed between said units whereby the units may be adjustably disposed in relation to each other.

3. A radiator core for internal combustion engines, comprising, a series of water 85 circulating units disposed in parallel relation to each other, and flexible strips disposed at opposite edges of the units and adapted to so space the units that the space 90 between the units may be varied.

4. A radiator core for internal combustion engines, comprising, a series of parallel water circulating units having oppositely and alternately disposed corrugations formed in the walls of said units and adapted to extend outwardly therefrom, convexed wall portions intermediate said corrugations, sinuous flexible strips secured along the opposite edges and between adjacent units whereby the units may be flexibly held in adjustable relation to each other.

In testimony whereof I have signed my name to this specification.

JAMES W. McFARLAND.
